UNITED STATES PATENT OFFICE.

ALEXANDER FÜRST, OF NEW YORK, N. Y., ASSIGNOR OF ONE-HALF TO CHARLES
EMIL POBE, OF NEW YORK, N. Y.

AUTOMOBILE-RADIATOR.

1,398,774.

Specification of Letters Patent. Patented Nov. 29, 1921.

Application filed June 20, 1919. Serial No. 305,452.

To all whom it may concern:

Be it known that I, ALEXANDER FÜRST, a citizen of the Republic of Hungary, but having declared my intention to become a citizen of the United States, and a resident of the city of New York, borough of Manhattan, in the county and State of New York, have invented a new and Improved Automobile-Radiator, of which the following is a full, clear, and exact description.

This invention relates to radiators for automobiles or the like and has particular reference to means for obtaining better control of the cooling of the water from the engine jacket than is ordinarily possible.

Among the objects of the invention is to provide a radiator, or what is the equivalent of the ordinary radiator, having the property of bringing the cooling air into direct contact with the water in the form of a fine spray or mist whereby the greatest cooling effect is accomplished.

Another object of the invention is to provide a means for readily varying the rapidity of circulation of the water so as to control in the best possible manner the degree or extent of cooling of the water according to the variations of temperature of the weather or like conditions.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a side elevation of my improvement showing its relation to a conventional type of engine.

Fig. 2 is a front elevation.

Fig. 3 is a vertical section of the radiator on the line 3—3 of Fig. 2; and

Fig. 4 is a horizontal sectional detail on the line 4—4 of Fig. 2.

Referring now more specifically to the drawings I indicate my invention as applied to an automobile engine 10 supported upon a frame 11 and having secured to and for communication with the cooling jacket a cold water admission pipe 12 and a hot water delivery pipe 13. Said pipe 12 is pro-

vided with a check valve 14, and the delivery pipe is fitted with a pump 15 of any suitable type for the purpose of causing a forced circulation of water through the engine jacket.

My improved cooling device for the water which will be referred to herein as the radiator is shown as a whole at 16, but instead of being designed to be maintained filled with water as is the usual practice it is filled chiefly with air but it has at the bottom a tray or pan 17 supplied with water to a sufficient depth to insure that the engine jacket and pipes 12 and 13 shall be kept full of water. The radiator in general design has the appearance of any usual radiator and includes a rim 18 having a front flange bounding or determining a large front opening 19, while the back wall 20 of the radiator is continuous except for a door 21 formed therein normally closed by a vertically movable slide 22 movable along guideways 23.

Just back of the plane of the front opening 19 are provided a vertical series of horizontal channels 24 constituting baffles. So far as the channels of water baffles 24 are concerned air may circulate freely and entirely around the same and along both the inner and outer surfaces. The ends of the water baffles 24 are open and free from the rim portion 18 of the radiator, as shown at 24^a. Each baffle as plainly indicated in Fig. 3 has an open front mouth 25 bounded above and below by flanges or lips 26.

The lowermost baffle 24 is similar to the others with respect to its upper portion, but its lower portion extends well down into the pan 17 and is sealed along said lower edge of the front flange portion of the rim 18 so as to constitute a front wall for the pan and so retain the water well spaced from the opening 19.

Each baffle 24, spaced from the next adjacent baffle, co-operates with an air baffle 27 which like the water baffles 24 is supported at its ends upon the rim of the radiator or may be made as an integral part of the rim structure. The front portion of each baffle 27 is projected forward in an obtuse angle, the apex of which at 27' is horizontal and extends well across the front of the radiator. The rear portions of each member 27 project inward through the mouth portions 25 of two adjacent water baffles 24, the upper rear portion of each baffle 27 projects down- 110

ward into the lower portion of the surrounding baffle 24, while the other or lower portion of the channel or baffle 27 projects upward into the upper portion of the next 5 lower baffle 24, but except for the attachment means between the two sets of baffles adjacent to the ends of the baffles 24, all parts of the baffles are spaced from one another. It will be seen, therefore, that air 10 will be admitted freely along the slots 28 between adjacent air baffles and such air will flow upward and downward along the inner surface of the water baffles 24 passing thence past the lips 26 into and along the interior 15 of the baffles 27 and thence inward through the slots 29 between adjacent baffles 24 into the interior of the radiator. Any suitable openings may be provided to facilitate the circulation of air inward and through the 20 radiator casing. To this end, the upper portion of the radiator may be provided with a plurality of apertures 34 of any suitable size which may operate as air vents so as to insure such a degree of circulation through 25 the radiator as may be required to secure the desired end. The radiator cap 30 may also be provided with a vent of the usual type but of a larger size than is usual.

The lower horizontal portion of the delivery pipe 13 may be termed a nozzle section 30 31 and may be located at any desired place with respect to the pan 17 lying either within the pan or below it. From this nozzle section there extend upward a series of 35 spraying nozzles 32 each of which is provided with an adjustable cock 33 to variably determine the amount of opening for the delivery of hot water upward from the nozzle section 31. The upper end of the spraying 40 nozzle 32 may have any suitable means such as a spiral plug of well known construction for the purpose of delivering the water in a fine mist or spray within the air chamber of the radiator. Obviously the delivery 45 ends of the nozzles extend upward above the level of the water in the pan irrespective of the location of the nozzle section 31. The admission pipe 12 leads from the lower portion 50 of the water jacket into communication with the body of water in the pan 17.

The operation may be briefly set forth as follows in view of the foregoing specific description of the construction. Assuming that the water jacket and pipe are filled 55 with water the pan 17 is supplied to the desired level and with the slide 22 closed as indicated in Fig. 3 the device is ready for operation. The pump 15 is adapted to be operated from the motor in any suitable 60 manner and when the motor is running the pump will be caused to operate and cause

thereby a forced circulation of water from the top of the engine jacket, a similar quantity of water being drawn upward through the pipe 12 into the jacket to take the place 65 of the water pumped therefrom. The water forced downward through the pipe 13 and nozzle 31 will be jetted upward through the spraying nozzles 32 as indicated in Fig. 70 3 forming a cloud of mist or the like within the radiator and in direct contact with cool air admitted thereinto through the slots 28 and 29. The delivery of the water in this manner into the interior of the radiator will tend to the vaporization thereof, but in any event whether the water is so delivered in the form of vapor or as a mist it is cooled rapidly by the air and is deposited into the pan 17 in the form of liquid at a much reduced temperature. There is no loss of water forward through the slots at the opening 75 at the front. Any water that may find its way into the interior of either set of channels 24 or 27 will flow freely along the gutters at the bottoms thereof and thence downward along the space 24^a at the rim portions of the radiator. In cool weather when a less amount of cooling of the water is desired than in summer the cocks 33 may be adjusted so as to throttle the amount of 80 discharge through the spraying nozzles. Thus the water will be kept warmer in the jacket. The slide 22 is ordinarily kept closed to prevent the loss of water or vapor from the radiator, but may be opened when necessary for the purpose of inspection of 85 the interior of the radiator. As before stated the cap 30 may constitute an air vent so as to allow a graduated amount of air to be delivered upward through the top of the 90 radiator to facilitate the circulation of air, especially in warm weather.

I claim:

1. In a device of the class set forth, a radiator having an open front for the free 105 admission of air and having a water pan at its bottom, air and water baffles arranged in said open front, each water baffle embracing but spaced from the adjacent portions of two adjacent air baffles, and means to deliver the water in the form of a spray into the interior of the radiator in direct communication with the air admitted through the open front.

2. A device as set forth in claim 1 in 115 which each pair of two adjacent air baffles comprise two flanges spaced from each other and projecting away from each other, and the water baffle embracing them is in the form of an open fronted channel.

ALEXANDER FÜRST.
